UNITED STATES PATENT OFFICE

LAWRENCE NERSINGER, OF ROCHESTER, NEW YORK, ASSIGNOR OF ONE-HALF TO JOHN R. STRANCHEN, OF SAME PLACE.

DEVICE FOR REPAIRING RUPTURES IN WATER-HOSE.

SPECIFICATION forming part of Letters Patent No. 257,602, dated May 9, 1882.

Application filed October 3, 1881. (No model.)

To all whom it may concern:

Be it known that I, LAWRENCE NERSINGER, of Rochester, Monroe county, New York, have invented a certain new and useful Improvement in Devices for Repairing Ruptures in Water-Hose; and I do hereby declare that the following is a full, clear, and exact description of the same, reference being had to the accompanying drawings, in which—

10 Figure 1 is a side elevation of a water-hose with my improvement applied thereto. Fig. 2 is a cross-section of the wrapper. Fig. 3 is a perspective view of the pivoted clamp and set-screw. Fig. 4 is a modification.

15 My improvement relates to that class of devices in which a flexible wrapper or patch is used, which envelops the ruptured hose, and is secured at the top by a clamping device.

The invention consists in the combination of 20 the metallic flanges attached to the edges of the wrapper, one or more clasps of peculiar construction pivoted to one of the flanges, and a set-screw passing through the clasp and striking under a rib of one of the flanges, as 25 hereinafter more fully described.

In the drawings, A represents a piece of ordinary water-hose, around which my improved device is wrapped.

B is the wrapper or patch, consisting of a 30 piece of rubber, rubber cloth, or other flexible material, of such length and size as to reach around the hose and cover the rupture.

C C' are right-angled metallic flanges attached fast to the meeting ends of the wrapper and abutting together, or nearly so, when 35 the wrapper is drawn up around the hose. The vertical portion of the flange C is plane or straight to receive the pivot of the clasp and allow the latter to work up and down freely in 40 opening and closing; but the other flange, C', has an outwardly-projecting rib, a, at its top, to hold the clamping-screw, as shown in the cross-section, Fig. 2.

D D are the clasps, of which either one or 45 two may be used. If two are used, they are located at opposite ends, as in Fig. 1. If one only is used, it extends the whole length of the flanges. Each of these clasps consists of a tang, b, which is pivoted at c to the flange C, and 50 of an offset body, d, having on its under side a groove or channel, f, of sufficient size to em-

brace the vertical parts of both flanges when nearly closed together, and in some cases the body may be made of such width as to embrace the flanges when they are at some distance apart, thereby adapting the wrapper to being drawn up more or less by the set-screw to fit larger or smaller hose. In Fig. 4 a single clasp is shown, pivoted at its opposite ends to the flange C, and turning over bodily to embrace the flanges. It might also be made to slide on the flanges, but not with so good effect.

E is the set-screw, of which one or more may be used. It passes through a hole in the side of the clasp and binds against the flange C' below the rib a, and thus forces the two flanges together and binds the wrapper tightly around the hose.

The object of the clasp is simply to close 70 down and secure the parts temporarily, after which the set screw or screws are forced up, the clasp in that case serving as a fulcrum and binding the wrapper so closely around the hose that leakage will be practically stopped. 75 The rib a serves as a stop to prevent the set-screw from slipping off and throwing the clasp open. One great advantage, as before described, is that the flanges can be brought loosely into the embrace of the clasp at some 80 distance apart, and then be forced together by the screw, thereby adapting the wrapper to different sizes of hose. The screw is more effective than cams or levers.

This invention is applicable to stiff as well 85 as flexible pipes.

What I claim is—

The combination of the pivoted clasp D, having the screw E passing through its side, and the metallic flanges C C', to one of which 90 the clasp is pivoted, the other being provided with a rib, a, beneath which the screw rests, as shown and described, and for the purpose specified.

In witness whereof I have hereunto signed 95 my name in the presence of two subscribing witnesses.

LAWRENCE NERSINGER.
